UNITED STATES PATENT OFFICE.

EDWARD N. SULLIVAN, OF BOSTON, MASSACHUSETTS.

RAILROAD-SIGNAL.

SPECIFICATION forming part of Letters Patent No. 242,712, dated June 7, 1881.

Application filed February 2, 1880.

To all whom it may concern:

Be it known that I, EDWARD NORRIS SULLIVAN, of Boston, in the county of Suffolk and State of Massachusetts, have invented a new and useful Improvement in Railroad-Signals, of which the following is a specification.

My invention relates to a means of operating railway-signals at such times as when the ordinary semaphoric signal cannot readily be seen.

10 The invention consists in operating a signal, indicated either by a light or by sound, or both, by means of a lever arranged at the side of a railroad-rail and actuated by the wheels of a passing locomotive or car, the said lever being set for action or inaction by means of a line or wire extending to a railroad-station or other distant point on the railroad.

Referring to the accompanying drawings, Figure 1 represents an elevation of a rail of a railway, and showing my appliances and their connections. Fig. 2 is an elevation of the inner side of the rail, and embodying my invention. Fig. 3 is a modification of the device. Fig. 4 is a plan or top view of my improvement.

25 *a* represents a rail of a railroad-track.

b is a section of angle-iron, arranged parallel with and on the outer side of rail *a*, and of any suitable length. The angle iron or rail *b* is supported upon steel springs *f f* at or near each 30 end, as shown in Fig. 2. The lower ends of the springs *f f* are secured in clips *e e*, bolted together, the lower one extending under the rail and passing up on the opposite side, and securely bolted to the rail *a*, as seen in Fig. 1.

35 The end of the angle iron or rail *b* upon which the wheel of the incoming train first passes is on a level with the rail *a*, but rises toward the other end, as shown, so as to modify the striking effect of the wheels.

40 *c* is a long lever, having its fulcrum at *d*, near the rail. The end of the shorter arm of lever *c* is connected to the under side of the angle iron or bar *b* by means of a swivel-joint, so as to admit of the lever being connected to the 45 air-cylinder at any desirable angle. The longer arm of lever *c* extends at an angle from the bar *b* any suitable distance, and is made flat toward its end, so as not to act with too sudden a force upon the piston in the air-cylinder, and 50 to allow of a more continued sound of the whistle. The end of the longer arm of lever *c*

is connected by means of jointed arms or links *h* to a piston-rod, *k*, on the lower end of which is a piston-head, *j*, working in an air chamber or cylinder, *l*.

55 To the top of the air-chamber *l* is attached a tube, *u*, forming a whistle, operated by the air as it is forced up by piston *j*.

To the upper end of piston-rod *k* is attached, by means of a bracket, *m*, a rod, *n*, having on its 60 upper end a red or colored glass disk, *o*, constituting a danger or warning signal when it covers the white light *p* in the lantern *q*, supported upon the frame *r*.

To the upper end of piston-rod *k* is attached 65 the line or wire *t*, which passes over pulley *s* and extends to the station or depot from which it is operated.

The piston-rod *k* may be surrounded by a spiral spring, as shown in dotted line in Fig. 1, 70 between the piston-head *j* and the top of cylinder *l*, so that the piston-head may not be forced up with too great velocity, and thus admit of a longer-continued sound of the whistle.

Instead of a whistle, a gong or bell may be 75 used as the audible signal, as shown in Fig. 3, in which the rope *t* is caused to raise the long arm of lever *c'*, having on its end a ball or tongue, *m'*, which strikes the gong *k'*.

The bar of angle-iron *b* may be of any desirable length. If a series of whistles or beats of the gong are considered necessary, the length of the bar *b* should be less than the space between the car-wheels.

The operation of my device is as follows: 85 When the track is clear, and no cautionary or danger signals are required to give warning to an approaching train, the line or wire *t* is drawn tight at the signal-station or depot, by which means the long arm of the lever *c* is elevated, 90 carrying up the rod *n* and the colored-glass disk *o*, and displaying the white light at *p*, indicating "all clear." At the same time the short arm of lever *c* and the bar *b* are depressed so as not to be affected by the passage of the wheels 95 of the train passing along the track. When the cautionary or danger signal is required the line or wire *t* is released from the signal-station, which causes the colored disk *o* to drop in front of the white light at *p*, indicating "danger," and bringing the short arm of lever *c* and the bar *b* into position to be operated by the 100

action of the passing train, and causing the whistle or gong to sound, thus giving warning to the incoming train.

What I claim as my invention is—

- 5 1. The combination of the rail or bar *b*, supported upon springs *ff* in bearings *ee*, the lever *c*, jointed arm *h*, piston *j*, and rod *k*, air-chamber *l*, whistle *u*, and rod *n*, carrying the disk *o*, all arranged for joint operation substantially as set forth.
2. The combination of the bar *b*, lever *c*, connection *h*, piston and rod *j k* with a cord or wire, *t*, extending to a distant station, by means

of which the lever *c* and bar *b* may be set for action or held in a position for non-action, substantially as specified.

3. The combination, with the bar *b*, of the springs *ff* and the clips or supports *ee*, secured to main rail *a*, as and for the purpose set forth.

In testimony whereof I have signed my name 20 to this specification in the presence of two subscribing witnesses.

E. NORRIS SULLIVAN.
